UNITED STATES PATENT OFFICE.

JAMES PHILIP ERIE, OF NEW YORK, N. Y., ASSIGNOR TO THE ERIE EXPLORATION COMPANY, OF SAME PLACE AND DOVER, DELAWARE.

CURRENT-REGULATOR.

SPECIFICATION forming part of Letters Patent No. 673,428, dated May 7, 1901.

Application filed September 17, 1900. Serial No. 30,346. (No model.)

To all whom it may concern:

Be it known that I, JAMES PHILIP ERIE, a citizen of the United States, residing in the city, county, and State of New York, have invented a certain new and useful Current-Regulator, of which the following is a specification.

My invention relates to current-regulators, and has for its objects to improve and simplify such devices and adapt them for the purpose more particularly set forth hereinafter; and to these ends my invention consists of a current-regulator embodying the features of construction and arrangement and having the mode of operation substantially as set forth.

Referring to the accompanying drawings, Figure 1 is a perspective view of a regulator embodying my invention. Fig. 2 is a front view showing the preferred arrangement of segments and the means for including a longer or shorter segment in the circuit. Fig. 3 is a similar view showing the parts in a different position. Fig. 4 is a partial side view, sectional view, and diagrammatic representation of the circuits, including the regulator; and Fig. 5 is a side view showing a modification.

In the practical utilization of electricity in connection with various translating devices it is common to provide a main or lead circuit carrying a current of constant potential or voltage and to include the translating devices in that lead or main line, so that they will take the current therefrom, and the quantity or amperes of current used will depend upon the character and use made of the translating devices. In connection with various forms of translating devices it is often desirable to utilize less than the normal quantity of current necessary to energize said translating devices to their full operative condition. For instance, in the use of motors, heaters, or lights included in the circuit, and which under normal conditions require a certain quantity of current to operate the motor at a given speed or power to energize the heater to produce a certain degree of heat or the lamp to produce a certain amount of illumination, a constant flow of current of a certain volume or quantity is required. It is often found desirable to energize such translating devices to a point below the normal or

full degree of energy, so as, for instance, to produce a less degree of illumination, heat, or power, and consequently utilize a less quantity of current, and the object of my current-regulator is to provide means whereby this may readily be done. This I accomplish, broadly stated, by cutting off the current from the translating device for a greater or less period of time, so that the current is allowed to flow to the translating device at relatively short intervals, which intervals, however, follow each other in rapid succession sufficient to produce the desired effects. Thus, for instance, ordinarily, when a motor, heater, light, or similar translating device is included in the circuit and it is desired to reduce the quantity of the current below the normal, resistance devices are interposed in the circuit of the translating devices and the current continues to flow through the resistance devices and translating devices, while the effect of the current on the translating devices is below that where the whole current flows directly and continuously through the translating devices. By my regulator instead of introducing resistance in the circuit of the translating device I rapidly cut the translating device in and out of circuit, so that the current does not flow through the translating device continuously, but at rapidly-recurring intervals, and these intervals of flow and stoppage of the current can be regulated and adjusted so as to produce the desired effect in the translating device.

With this general statement of my invention I will now proceed to describe the preferred embodiment thereof illustrated in the accompanying drawings.

In the drawings, A represents any suitable base, upon which is mounted an electric motor B, of any suitable construction and having an armature-shaft B', and in this instance mounted upon and insulated from an extension B² of the armature-shaft B' is a ring C, so arranged as to rotate with the armature-shaft. Also mounted on the base by a suitable standard A' is an insulating-plate D, which may form a bearing for the extension B² of the shaft and which supports and carries a number of segments E E² E³ E⁴. Also supported on the base is

a carrier F, of insulating material, supporting a number of connectors G G' G² G³, shown in the present instance in the form of metallic spring-plates secured to the periphery of the carrier F and having arms g g' bearing on the periphery or peripheries of the segments E to E⁴. Any other form of carrier and connector may be used which will accomplish a like purpose, the form shown being simple and cheap of construction and preferred. Also mounted on the carrier is a handle or thumb-piece F' for adjusting the carrier, and to aid in adjusting the same to the proper position there is an index F², in this instance arranged on the periphery.

Some suitable means must be used for connecting the insulated ring with the segments, and I have shown a spring brush or contact H connected to the ring and adapted to bear on the faces of the segments E to E⁴, and there is a stationary brush or contact H' supported on an arm H², mounted on but insulated from the motor, bearing on the face of the ring. For convenience, mounted on the motor is an insulating-plate I, having a number of binding-posts i i' i² i³ i⁴, and there is also provided a switch J, having switch-arms J' J², connected together by an insulating-link J³ and operated by a handle J⁴, and there are also mounted on the base binding-posts a a', and the parts are suitably connected electrically, as more fully indicated in Fig. 4. While in the present instance I have shown in Figs. 1, 2, and 3 five segments E to E⁴, any desired number may be utilized, according to the needs of the particular use of the device, and there of course will be a corresponding number of connectors G. In this instance these parts are so arranged that in their normal positions (shown in Fig. 2) the connector G is included directly in the circuit, and its ends or arms g g' both bear on the periphery of the segment E. The connector G' is similarly arranged, so that its ends are within the area of segment E', and so of the other connectors and their respective segments. When, however, the carrier F is moved to the right, as shown in Fig. 2, one end or arm g of the connector G bears on the segment E and the other end or arm g' bears on the segment E', as shown in dotted lines, so that the two segments E and E' are electrically connected or so arranged as to practically make a longer segment, including the segments E and E'. When the carrier is moved farther, the arm g' of the connector G' bears on the segment E², while the other arm g of said connector bears on the segment E', and in this way the segments E, E', and E² are electrically connected together, forming a long segment equivalent to the extent of the segments E E' E², and so on as the carrier is rotated other segments are electrically connected until, as shown in Fig. 3, the arm g' of the connector G³ bears upon the segment E⁴, while the arm g of the said connector bears on the segment E³, and the arms of the other connectors G G' G² also bear upon two of the

adjacent segments, so that all of the segments are electrically forming practically a continuous segment equivalent in length to the sum of the segments E to E⁴, and the current flowing through the regulator is continuous. Of course when only one segment, as E, is electrically connected with the circuit as the brush or contact H moves over the face of the segments current flows through the brush only during the period of time occupied in moving the brush over the face of the segment E, and the circuit is broken while the brush passes over the segments E' to E⁴, and when the segments E and E' are electrically connected by the connector G and the brush H rotates current flows through the brush during the period it is passing over said segments E E' and the circuit is broken as the brush passes over segments E² to E⁴. It will thus be seen that by adjusting the carrier and its connectors the circuit can be opened or closed throughout a greater or less portion of the time of rotation of the brush or contact H, or, in other words, a longer or shorter segment may be included in the circuit, so that the relative periods of flow of current or stoppage of the flow of current can be changed and regulated to suit the wishes of the operator. In this way it will be seen that any translating devices connected in the circuit including the brush H will be periodically energized by the electric current or deenergized, and as these periods are relatively very short the alternate makes and breaks of the circuit will not be perceptible to the eye in the translating devices, but the effect will be to reduce the energy supplied to those translating devices, and the motor will rotate with less speed or power, the heater be less hot, and the lamp give less illumination in accordance with the relative periods of flow or stoppage of the flow of current to the translating devices.

Referring to Fig. 4, one arrangement of circuits is therein shown, which will be understood by those skilled in the art, but which may be traced as follows: Starting from the generator X, the current flows through the conductor 1 to the binding-post i on the generator, thence by the conductor 2 to the contact j on the switch J, through the arm J² by the conductor 3 to the binding-post a', thence by conductor 4 to the field-magnet coils, through the same to one terminal of the armature-coils of the motor, through said coils and by the conductor 5 to the binding-post a, thence by the conductor 6 to the binding-post i⁴ and conductor 7 to the terminal of the generator X. A branch circuit from the generator flows through the conductor 8 to the binding-post i², thence through the conductor 9 to the contact j' of the switch, through switch-arm J' by conductor 10 to the connector G, through the arms g g' of the connector to the segment E, thence to the brush H, ring C, brush H', conductor 11, binding-post i³, conductor 12, to the translating de-

5 vices $T T' T^2$, and thence by the conductor 13 to the terminal of the generator. In this case the translating device T represents a lamp, T' a heater, and T^2 a motor, and there are suitable switches $t t' t^2$, so that either one or more of the translating devices may be included in the circuit of the generator and regulator. The switch J is simply a convenient means of controlling both the circuits of the 10 motor and of the regulator simultaneously and may or may not be used, according to the particular arrangement of circuits.

In Fig. 5 I have shown a modification of my invention wherein the segments rotate, and in this case the extension B^2 of the armature-shaft carries a cylinder M , having a series of segments $m m' m^2$, &c., of different lengths on its periphery, all of which are connected electrically to the conductor leading from the 15 generator, and there is a brush H^3 mounted on a suitable support H^4 , so that it can be adjusted to bear upon the periphery of any one of the segments $m m'$, &c., and this is electrically connected with a brush H^5 , which in 20 turn leads to one terminal of the translating device T^4 , the other terminal of which is connected to the generator, and it will be seen that by moving brush H^3 so that it will bear on the segment of different lengths the period 25 of time when the current will flow to the translating device T^4 and when it will be stopped with relation to the rotation of the drum will be varied.

Having thus described the general principles of my invention and illustrated means for carrying it out, it will be understood that it is not limited to the precise details of construction and arrangement shown, as these may be varied by those skilled in the art to 35 suit the particular purposes desired. It will be seen, however, that my current-regulator comprises a series of segments and means for electrically including a longer or shorter segment in the circuit, so that the current 40 through the brush or contact bearing on the segment or segments is caused to pass over their surfaces and will be allowed to flow for a greater or less period of time and the flow be stopped for a greater or less period of time, 45 and these periods are rapidly recurring and follow each other alternately, or the circuit 50

may be arranged so that the current will flow continuously to the translating devices.

What I claim is—

1. A current-regulator comprising a series 55 of separately-insulated segments, means for electrically including a longer or shorter segment in the circuit, a brush or contact for the segments, and means for moving the brush and segments with relation to each other, 60 substantially as described.

2. A current-regulator comprising a series of segments, means for electrically including more or less of the segments in the circuit, a brush or contact for the segments, and means 65 for rotating the brush and segments with relation to each other, substantially as described.

3. A current-regulator comprising a series 70 of segments, a carrier, a series of connectors moved by the carrier to include more or less of the segments in the circuit, a brush or contact, and means for rotating the brush and segments with relation to each other, substantially as described.

4. A current-regulator comprising a stationary series of segments, a carrier adjustable with relation thereto, connectors mounted on the carrier for including more or less of the segments in the circuit, a motor, and a brush 80 or contact carried by the motor and bearing on the segments, substantially as described.

5. A current-regulator comprising a stationary series of segments, a carrier adjustable with relation thereto, connectors mounted on 85 the carrier and adapted to connect one or more of the segments in electric circuit, a motor, an insulated ring mounted on and driven by the motor, a brush mounted on the ring and bearing on the segments, a stationary 90 brush bearing on the ring, and electric connections substantially as shown whereby the motor is rotated and the current through the regulator controlled, substantially as described.

In testimony whereof I have signed my name to this specification in the presence of two subscribing witnesses.

JAMES PHILIP ERIE.
